PENCIL

Filed Sept. 19, 1924

FIG. 1

FIG. 2

INVENTOR

John H. Fischer

BY

Cooper, Kent & Aukerman ATTORNEY

UNITED STATES PATENT OFFICE.

JOHN H. FISCHER, OF NEW YORK, N. Y., ASSIGNOR TO EAGLE PENCIL COMPANY, OF NEW YORK, N. Y., A CORPORATION OF NEW YORK.

PENCIL.

Application filed September 19, 1924. Serial No. 733,594.

The invention subject of the present application for Letters Patent is an improvement in pencils. The effect sought in the development of this device was the production of a mechanical pencil of this general character, in which by the simple turning of the cap at the rear end of the case the lead might be advanced or retracted or expelled from the case. In accomplishing this I have devised a propelling and retracting device which affords a spring seat for the lead, whereby the latter, in use, yields under any undue pressure and thus saves the lead from being broken. At the same time the spring seat or holder for the lead is so designed and combined with the propelling rod that the lead, if any, remaining in the seat may be at once expelled by forcing forward the propelling rod and thereby compressing the spring against a flange in the tapered end of the case and thereby causing the rod to force out the lead.

In shop parlance, therefore, the new device is a propel, retract and expel pencil, and is distinguished by extreme simplicity and durability. I refer now to the accompanying drawing in illustration of the improvement.

Fig. 1 is a central longitudinal part section of the complete pencil.

Fig. 2 is a similar view on an enlarged scale, of the forward portion of the case.

Fig. 3 is a cross section on the line 3—3 of Fig. 2.

In many respects the construction of the pencil follows known and usual lines. It comprises a case 1, tapered at the forward end, containing a contracted guide cylinder 2 to which is secured a spiral wire 3. A cylinder 4 fits into the open rear end of the case and is closed by a rubber eraser 5, to form a reservoir for the storage of extra leads. Beyond this reservoir the cylinder is extended in smaller diameter 6 to practically the end of the tapered portion of the case.

For a given distance the reduced portion 6 is longitudinally slotted and it contains a rod 7 with a bent end 8 that extends out through the slot 11. Over the forward or free end of the rod 7 is a spiral spring 9 secured to the said rod at 10 and extending down beyond the end of said rod to a short distance about the length of an ordinary lead, towards the opening in the tapered end.

The end of this spring serves as the seat

and holder for a lead 13 which is inserted 55 through the opening in the tapered end of the case and into the open end of the spring after the rod 10 has been slightly retracted.

The cylinder 4 is permanently secured in the case and is adapted to turn therein in the usual manner. Over its end fits a cap 12 of the usual character, which fits tightly enough to turn the cylinder, and, in general, these parts of the pencil are not new and may be greatly modified if so desired.

When a lead has been inserted through the tapered end into the open end of the spring 9, the cylinder 4, the bent end 8 of the rod 7 engaging the spiral wire 3 secured to the part 2, is turned, whereupon the rod 7 travels 70 down through the portion of reduced diameter 6 and exposes more or less of the lead, or when the cylinder is turned in the opposite direction the lead is retracted into the case. If a slight space remain between the 75 end of the rod 7 and the lead, the latter will be held in a spring seat which yields under pressure upon the end of the lead.

When the lead is worn down the short stub remaining in the spring may be readily 80 expelled by turning the cap until the rod 10 forces the end of the spring 9 against a flange 14, whereupon the spring is compressed and the rod forces the lead out.

This is an extremely simple and durable 85 pencil which has many new and very useful features, the result of the constructions defined in the following claims.

What I claim is:

1. In a device of the character described, 90 a helix, a tube within the helix provided with a longitudinal slot, a lead feeding rod within the tube having a projection extending out through the slot in the tube into engagement with the helix, a helical spring surrounding 95 the rod and attached at one end to the rod at some distance from the lead engaging end of the rod, the spring projecting far enough beyond said lead engaging end of the rod to clutch the lead, and connections whereby relative movements of the helix and slotted tube may be effected to actuate the rod and spring to retract and propel the lead.

2. In a device of the character described, 105 a helix, a tube within the helix provided with a longitudinal slot, a lead feeding rod within the tube having a portion projecting through the slot in the tube into engagement with the

helix, a helical spring within the tube attached at one end to the rod at some distance from the lead engaging end of the rod and projecting far enough beyond said lead engaging end to clutch a lead, an abutment adjacent the writing end of the pencil against which said spring may be compressed by final expelling movement of the propelling rod, and connections whereby relative movement 10 of the helix and slotted tube may be effected to actuate the rod and spring to retract, propel and expel the lead.

3. In a mechanical pencil the combination of a barrel and a tip, a coiled spring adapted 15 to grip a lead by means of its coils, means for moving the spring longitudinally of the barrel to feed the lead, means for arresting the end of the spring and an ejector movable relatively to the spring for ejecting the lead 20 from the spring and through the tip.

4. In a mechanical pencil the combination of a barrel having a tip, an ejector rod having a coiled flexible member concentrically surrounding it and projecting beyond the end 25 thereof, and having an open end adapted to receive and grip a lead, means for moving the rod and flexible member longitudinally of the barrel to feed the lead and means for automatically arresting movement of the flexible member during the end of the feeding 30

movement to cause the ejection of the lead therefrom.

5. In a mechanical pencil the combination of a barrel having a tip, a hollow, longitudinally compressible member in said barrel and 35 adapted to receive and grip a lead in its open end and means for moving the member longitudinally of the barrel to feed the lead through the tip and means for arresting forward movement of the compressible member 40 during its compression for permitting release of the lead.

6. In a mechanical pencil the combination of a barrel having a tip, and a hollow lead carrier movable longitudinally of the barrel, 45 said carrier having a coiled open end adapted to receive and grip a lead, means to cause the longitudinal compression of said coiled end and means to prevent lateral movement of the coils during their compression.

7. In a mechanical pencil the combination of a barrel having a tip and a lead carrier comprising a coil adapted to grip a lead in its open end, and means for causing the direct longitudinal compression of the coil for 50 causing the end of the coil to release its grip on the lead.

In testimony whereof I hereto affix my signature.

JOHN H. FISCHER.
